The figure is a surface view of a piece of textile fabric or the like, showing the design. The area within the dot and dash lines shows

one complete unit of the design. The repeats are arranged in vertical rows, and adjacent vertical rows are one half a complete unit offset so that the angle of the complete unit indicated by letter A corresponds with angle B of one of the repeats in an adjacent vertical row.

I claim:

The ornamental design for a textile fabric or the like, as shown and described.

JAMES VILLANI.
